UNITED STATES PATENT OFFICE.

EGBERT O. DOAK, OF CANISTOTA, SOUTH DAKOTA.

DIFFERENTIAL.

Application filed September 17, 1924. Serial No. 738,124.

To all whom it may concern:

Be it known that I, EGBERT O. DOAK, a citizen of the United States, and a resident of Canistota, in the county of McCook and State of South Dakota, have invented certain new and useful Improvements in Differentials, of which the following is a specification.

My invention relates to a differential for 10 automotive vehicles, and it is my object to provide a differential of simple, durable and inexpensive construction.

The main purpose of my invention is to provide a differential which will accomplish the object of allowing varying ratios of speed between the rear wheels of a car when being driven in a circular path, but which will eliminate the possibility of one wheel remaining stationary while the other 20 is driven forward at a doubled rate of speed.

Stated in another way, my invention contemplates the positive driving of both rear wheels of a car at a definite speed determined by the propeller shaft velocity, the 25 varying ration of speeds between the rear wheels being accomplished by allowing either of the wheels to idle ahead at a rate faster than the rate of rotation positively communicated from the propeller shaft.

30 A further object is to provide means for positively transmitting the power from the propeller shaft to the rear axles of a car in either forward or reversed direction, which will yet allow the rear axle shafts to differential in either forward or reverse directions of rotation.

More specifically, referring to the latter object, it is my aim to provide two series of 40 power-transmitting links adapted to selectively connect the propelling mechanism with the driven axles so as to positively transmit power to the axles in the direction of rotation of the propelling mechanism, and simultaneously to allow faster rotation of 45 either driven axle, either series of power-transmitting links being movable into operative position automatically by the rotation of the propelling mechanism in the direction in which the particular series is 50 adapted to positively transmit rotation, the other series being simultaneously moved out of operative position by the same factor.

A still further object is to provide actuating means for accomplishing the above ob-

ject, controlled by the retarding resistance 55 to rotation of the driven axles.

Another object is to provide such an actuating means which is controlled by frictional engagement between the ends of the 60 axles.

With these and other objects in view, my invention consists in the construction, arrangement and combination of the various parts of my device, whereby the objects contemplated are attained, as hereinafter more 65 fully set forth, pointed out in my claims and illustrated in the accompanying drawings, in which:

Fig. 1 is a horizontal, sectional view through the rear axle, differential and propeller shaft housing in an automotive vehicle, illustrating my invention in plan, a portion of the casing being broken away in order to better illustrate the parts. 70

Fig. 2 is a detail, vertical, longitudinal, 75 sectional view through the differential mechanism, taken on the line 2—2 of Fig. 1.

Fig. 3 is a vertical, transverse, sectional view, taken on the line 3—3 of Fig. 2.

Fig. 4 is a perspective view of a pair of 80 power-transmitting links.

Fig. 5 is an enlarged, diagrammatic, figure illustrating the construction and arrangement of the power-transmitting link and ratchet wheel relative to each other. 85

Fig. 6 is a sectional view, similar to Fig. 3, of a slightly modified form of my invention.

A defect that is inherent in the ordinary differential mechanism in use on cars is that 90 one of the rear wheels of the car may become stuck and secured against rotation, and the power will continue to be transmitted to the other wheel alone, which will spin at a speed double the normal speed of the rear 95 wheels relative to the propeller shaft speed. My invention is primarily designed to eliminate this objection by providing a positive driving connection between the propeller shaft and each of the rear axle shafts. 100

I have used the reference character 10 to indicate the combined rear axle and differential housing, which is of the ordinary construction. To it is bolted the propeller shaft housing 11, in the rear end of which 105 is rotatably mounted in roller bearings, 12, the driving pinion, 13.

The rear axle shafts, 14, are journaled at

their inner ends against the roller bearings, 15, received in the housing, 10. At their inner ends the shafts, 14, are separated by a suitable washer or spacing disk, 16. It is understood that the construction just described is common and that there is no operative connection between the two axles, 14.

In the ordinary construction the inner ends of the axles, 14, are keyed by means of keys, 17, mounted in the key-ways, 18, to gears which form part of the differential mechanism.

In my invention these gears are removed and in their place are substituted the ratchet wheels, 19, which are keyed to the shaft in the same manner and held against longitudinal movement by the same rings, 20, used in the old construction.

It may be mentioned here that the teeth, 21, of the ratchet wheels are square in cross-section, as illustrated in Figs. 3 and 5. The purpose of this construction will later be more fully explained.

The hubs, 22, of the ratchet wheels, 19, are slightly reduced so as to form the shoulders, 23.

The differential mechanism is supported in a housing, composed of the ring gear, 24, and the end plate, 25, which are provided with central circular openings through which the hubs, 22, of the ratchets project. The members, 24 and 25, are secured together at the periphery of the plate, 25, by the arched plates, 26. Screws, 27, received through openings in the members, 24 and 25, and threaded into the plates, 26, are used for this purpose. When assembled, the members, 24 and 25, snugly engage the shoulders, 23, of the ratchet wheels, 19, in order to secure them against outward movement.

I provide the flanged sleeves, 28, which, engaged between the inwardly-extending bearing-retaining sleeves, 29, of the casing, 10, through the medium of the friction washers, 30; and the outer faces of the members, 24 and 25, respectively, serve to position the differential mechanism when the halves of the housing, 10, are secured together, and to maintain the engagement of the teeth, 31, of the ring gear, 24, with the pinion, 13. It will be understood that the friction washers, 30, are of the ordinary construction.

It will now be seen that the unit comprising the members, 24, 25 and 26 is rotatably mounted relative to the shafts, 14, on the hubs, 22, of the ratchet wheels. In order to transmit rotation from this unit to the ratchets, I provide the pairs of pawls, 32, which are pivotally mounted on bolts, 33, supported between the members, 24 and 25, respectively. In the form of my invention illustrated herewith, I have shown three

of such pairs of pawls equi-distantly spaced around each of the ratchets, 19. It will be understood that more or less might be utilized, but I find that three or four pairs prove the most practical.

Referring to Fig. 4, it will be noted that the free end of each pawl is enlarged so as to occupy the entire width of the space in which the pivoted shanks, 34, of the pawls are confined. The width of these engaging teeth, 35, is the same as the width of the teeth, 21, of the ratchets. Thus I obtain a maximum of strength in a minimum of space, the outer portions of the pawls which never come together overlapping each other.

It will now be seen that the pawls are so arranged that either one may form a driving connection between the gear, 24, and the ratchets, 19, so as to positively transmit rotation to the ratchets in the direction of rotation of the gear, but to allow rotation of the ratchets at a rate faster than the rotation of the gear. In order to accomplish this only one series of the pawls, those disposed in the direction of rotation of the gear, may be allowed to engage the ratchets at one time. In order to control this engagement of the pawls I provide the following mechanism.

Between the inner ends of the ratchets, 19, and rotatably mounted on the inner ends of the axle shafts, 14, by means of the hub, 36, is a disk, 37, which separates the pawls engaged with one ratchet from those engaged with the other. The hub, 36, extends in either direction from the disk, 37, and is rotatably received within the ratchets, 19, which are provided with enlarged bores for that purpose. Between the edges of the hub, 36, and the shoulders, 38, formed by the enlarged bore and received within said bore, are the springs, 39, which are of relatively heavy material. The object of these springs is to provide a resilient, frictional connection between the ratchets, 19, and the plate, 37, so that when the direction of rotation of the pawl, 24, is reversed this friction will retard the rotation of the plate, 37, in the new direction. This retarding action shifts the pawls, 32, into the position required by the change in rotation, as will now be explained.

Pins, 40, are securely mounted in the plate, 37, extending from either side thereof, and are received between the pawls, 32 of each pair. Springs, 41, maintain the engagement of the pawls, 32, with the pins, 40, tending to draw the pawls toward each other.

Shouldered bolts, 42, secured to the members, 24 and 25, respectively, pass through slots, 43, in the plate, 37, and serve to limit the movement of the plate relative to the ring gear, 24. The bolts, 42, also serve as a bracing means to space the members, 24 and 25, apart in addition to the plates, 26.

The bolts, 42, may be dispensed with as far as their function in limiting the movement of the plate, 37, is concerned, and the bolts, 33, allowed to perform that function. A modified form in which this is accomplished is illustrated in Fig. 6, in which the plate, 37, has formed on its periphery a pair of spaced lugs, 44, the path of which is intercepted by the bolt, 33.

Referring now to the operation of the device and for illustration to Fig. 3, it will be assumed that the ring gear, 24, is rotating in the direction indicated by the arrow, 45. The force opposed to the pulling power of the propelling means which tends to retard the rotation of the shafts, 14, and ratchets, 19, frictionally operating upon the plate, 37, through the medium of the springs, 39, will maintain the plate, 37, in the position shown in Fig. 3. In this position the pins, 40, being positioned a little to the rear of the bolts, 33, in the direction of rotation, will maintain one of the pawls of each pair out of engagement with the ratchets, 19.

For convenience in describing the operation, I will refer to this series of pawls, which is inoperative when the ratchet is being driven forward, as the pawls, B, and the other series as the pawls, A.

At the same time the pawls, A, will be allowed to remain in engagement with the ratchet wheels, and will transmit positively the rotation of the gear, 24 to the ratchet wheels. In going around a corner the wheel on the outside, traveling through a larger arc, will be caused to rotate at a rate faster than that of the wheel on the inside. The car will then be driven entirely from the inner wheel, and the outer wheel will idle forward at the proper speed, the ratchet on the outer shaft being allowed thus to rotate by the pawls, A. It will be noted that when this occurs the rotational friction against the plate, 37, of the two ratchets, instead of being in the same direction will be in opposite directions, the two forces tending to neutralize each other. However, in addition to the retarding force exerted by the ratchet on the axle which is driving the car, my device provides an additional factor tending to maintain the plate, 37, in its initial position.

Referring now to Fig. 5, it will be noted that the face of the ratchet tooth, 21, is inclined toward the bolt, 33, within the arc of movement of each of the teeth, 35, as indicated by the broken line, 46. Thus any tendency of the pawl, 32, to disengage itself from the ratchet would at the same time tend to force the ratchet ahead against its resistance to rotation. Since this force is considerable, it will be seen that the pawls, 32, will be securely locked in position and will thus retain the plate, 37, against this unwanted movement.

Assuming that the car is still moving for-

ward and the driver wishes to retain the engine in gear while coasting down hill in order to drive his generator, it will be seen that the propeller shaft will now provide the retarding resistance and the wheels will be driven forward positively, thus rotating the ratchets, 19, forwardly relative to the ring gear, 24. The frictional engagement of the ratchets will also carry the plate, 37, in the direction indicated by the arrow, 47, until the slot, 43, limits the motion of the plate relative to the ring gear. This forward rotation of the plate carries the pawls, A, out of engagement with the ratchets and lowers the pawls, B, to position where the forward rotation of the ratchets will, through the pawls, B, transmit rotation to the ring gear, 24, in order to drive the engine forwardly. When the driver shifts gears and causes the propeller shaft to rotate in a reverse direction, the same operation is effected as that just described. The ring gear rotates rearwardly and the plate, 37, is held against rotation by the frictional resistance of the ratchets. It will be seen that the same differential action will take place in driving the car around a curve backward as in driving forward around a corner.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In a differential, driven elements and a driving element, the latter carrying two series, oppositely disposed, of power transmitting links movable alternately to positions for rotating the driven element in either direction, and means controlled by the retarding resistance to rotation of the driven elements, for simultaneously moving one series of links to operative, and the other series to inoperative position, said means including a single plate frictionally engaged between the driven elements, and projections carried by the plate engaged with the links the power transmitting links being arranged to resist disengagement from the driven element when in engagement therewith.

2. In a differential, driven elements and a driving element, the latter carrying two series, oppositely disposed, of power transmitting links movable alternately to positions for rotating the driven element in either direction, and means controlled by the retarding resistance to rotation of the driven elements, for simultaneously moving one series of links to operative, and the other series to inoperative position, said means including a single plate frictionally engaged between the driven elements, projections carried by

the plate engaged with the links, and means for limiting the movement of the plate relative to the driving element the power transmitting links being arranged to resist disengagement from the driven element when in engagement therewith.

3. In combination with the driven axles of an automotive vehicle, a pair of ratchet wheels on the abutting ends of said axles, a plurality of pairs of pawls, oppositely directed and engageable with the ratchets, each pair being pivoted on a single stud carried by a driving element, a plate frictionally engaged between the ratchet wheels and carrying a plurality of projections each projection being engaged between the pawls and in contact with each pawl of its respective pair and adapted to retain one pawl of each pair out of engagement with the ratchet wheels.

4. In combination with the driven axles of an automotive vehicle, a pair of ratchet wheels on the abutting ends of said axles, a plurality of pairs of pawls, oppositely directed, pivoted on a driving element, and engageable with the ratchets, and means actuated by rotation of the driving element in either direction, for bringing into operative engagement with the ratchet wheels, the pawls directed to rotate the axles in that direction, said means including a plate having a hub rotatably mounted on the abutting ends of the axles, the ratchet wheels being recessed to receive the ends of the hub, and coil springs surrounding the axles and engaged between the wheels and the hub.

5. In a differential, in combination with the driven axles of an automotive vehicle, a pair of ratchet wheels on the abutting ends of said axles, a driving element, including spaced side members, shafts connecting said side members, a friction plate rotatably mounted on the abutting ends of the shafts and frictionally engaged between said ratchet wheels, a series of pairs of oppositely disposed pawls mounted on the shafts on either side of said plate, the plate serving to separate the series of pairs on one side from that on the other, and means carried by the plate to bring into engagement with the ratchet wheels, the pawls directed to transmit rotation in the direction of rotation of the driving element.

6. In a differential, in combination with the driven axles of an automotive vehicle, a pair of ratchet wheels on the abutting ends of said axles, a driving element, including spaced side members, shafts connecting said side members, a friction plate rotatably mounted on the abutting ends of the shafts and frictionally engaged between said ratchet wheels, a series of pairs of oppositely disposed pawls mounted on the shafts on either side of said plate, the plate serving to separate the series of pairs on one side

from that on the other, the two pawls of each pair being widened at their engaging ends so as to overlie each other, and means carried by the plate to bring into engagement with the ratchet wheels the pawls directed to transmit rotation in the direction of rotation of the driving element.

7. In a differential, in combination with the driven axles of an automotive vehicle, a pair of ratchet wheels on the abutting ends of said axles, a driving element, including spaced side members, shafts connecting said side members, a friction plate rotatably mounted on the abutting ends of the shafts and frictionally engaged between said ratchet wheels, a series of pairs of oppositely disposed pawls mounted on the shafts on either side of said plate, the plate serving to separate the series of pairs on one side from that on the other, tension springs connecting the two pawls of each pair and disposed in the planes separating the pawls of each pair, and studs extending through the plate and engaging each pawl of the respective pairs, said studs being disposed between the pawls and the springs.

8. In a differential, in combination with the driven axles of an automotive vehicle, a pair of ratchet wheels on the abutting ends of said axles provided with annular recesses, a friction plate having a hub rotatably mounted on the ends of the axles and enclosed in the recessed portions of the ratchet wheels, coil springs engaged between the ratchet wheels and the ends of the hub, in said recesses, the ratchet wheels being provided with reduced hubs, a driving element including two side members journaled on said reduced hubs and engaged against the sides of the ratchet wheels, shafts connecting the two side members, a series of pairs of oppositely disposed pawls pivoted on the shafts, on either side of the plate, the plate serving to space the two series apart, springs connecting the two pawls of each pair, and studs carried by the plate, projecting between the springs and pawls of each pair, engaging each pawl of each pair.

9. In a differential, in combination with the driven axles of an automotive vehicle, a pair of ratchets mounted on the abutting ends of the axles, a relatively thin friction disk rotatably mounted on the abutting ends of the axles and received between the spaced sides of the ratchets, a driving member, a series of pairs of oppositely disposed pawls pivoted on the driving member on either side of the plate, the two pawls of each pair being connected by tension springs, studs carried by the plate and projecting in either direction, the respective ends of each stud being engaged between the pawls and spring respectively of the adjacent pairs, and simultaneously engaging each pawl of the respective pairs, the pawls being provided

with engaging ends engageable with the ratchet teeth, the ratchet teeth being inclined toward the shafts and within the arcs of swing of the engaging ends of the pawls.

- 5 10. In combination with the driven axles of an automotive vehicle, a pair of ratchets mounted on the abutting ends of the axles, and having reduced hubs, a driving member comprising a pair of side elements rotatably mounted on said hubs, casing members removably connecting said side elements in positions engaging the faces of the ratchets, the ratchets being recessed on their inner faces next to the axles, a friction disk engaged between the opposed faces of the

ratchets and having a hub rotatably mounted on the axles and received within the recessed portions of the ratchets, a series of pairs of oppositely disposed pawls pivoted on the driving member on either side of the 20 disk and engageable with the ratchets, and means carried by the disk for bringing into engagement with the ratchets, those pawls which are directed to transmit rotation from the driving member to the axles in the direction of rotation of the driving member. 25

Signed at Canistota, in the county of McCook and State of So. Dak., this 12th day of September, 1924.

EGBERT O. DOAK.
